CHILLING APPARATUS

Heinrich Süss, Berlin-Tegel, Germany, assignor
to Rheinmetall-Borsig Aktiengesellschaft Werk
Borsig Berlin-Tegel, Berlin-Tegel, Germany

Application January 28, 1939, Serial No. 253,425
In Germany February 5, 1938

11 Claims. (Cl. 62—126)

Chilling apparatus as employed for freeing mineral oils from paraffin are mostly designed as horizontal, jacketed tube coolers, the individual jacketed tubes being arranged, two by two, in a large number of superposed tiers. The mixture of oil and solvent flows through the inner tubes, which are connected to form a continuous conduit by bends arranged alternately at their ends, whilst the cooling means is passed through 5 the annular space between the outer tubes or jackets and the inner tubes.

The cooling means consist of media of low boiling points, and especially liquefied gases (e. g., NH₃ or SO₂), and the operations are usually conducted on the flooding principle. The cooling medium flows from a reservoir (flooder) located above the jacketed tubes, through a down pipe, to the end of the jacket space of the tubes, and is returned—by thermo-siphon action and in 10 the condition of a specifically lighter mixture of liquid and vapour—at the other end, to the flooder. There, a separation of the gaseous and liquid portions occurs in known manner, the vaporised cooling medium being drawn off by a compressor 15 (refrigerating machine) whilst such of the medium as has not yet vaporised is returned directly to circulation in the chiller.

A defect of this method, as hitherto applied to chilling apparatus, consists in that, in the case 20 of substantial structural heights for example, with more than six superposed tiers of jacketed tubes, the hydrostatic pressure of the liquid cooling medium in the lowest rows of tubes considerably retards the evaporation of the cooling medium, and thus correspondingly reduces the cooling capacity. This defect becomes specially manifest, as a source of trouble, when, for operative reasons, it is necessary to work with cooling media which produce large volumes of 25 vapour, or cooling media of high specific gravity, such as SO₂. In such cases, the most favourable evaporation and cooling effects are obtained when the layer of cooling medium is kept as shallow as possible, and the resulting vapour is led away 30 as quickly as possible. Hitherto, in attempting to achieve this result, the cooling medium has been allowed to overflow, like a cascade, from one cooling tube to another, and small vapour spaces have been left at the crown of each tube. Such apparatus has the defect of requiring the provision 35 of lateral extensions, with numerous flanged joints which lead to leakage and appreciable loss of refrigeration.

The present invention achieves the object of 40 obtaining, in all the cooling tubes and independ-

ently of the total height of the apparatus, a uniform evaporation of the cooling medium in a shallow layer, by means of a special arrangement of headers serving to accommodate the ends of the cooling tubes and the bearings of the 5 scraper shafts.

A typical embodiment of the invention is illustrated in the accompanying drawing.

Fig. 1 is a side elevation, in partial section, of the chilling apparatus as a whole.

Fig. 2 is a partial plan.

Fig. 3 represents a vertical section through one of the end supporting frames constituted by the aforementioned headers.

The apparatus comprises, as usual, a plurality 15 of superposed tubes 8, 9 surrounded each by a jacket or outer tube 1 and connected together by bends 2 to form a continuous conduit for the substance to be treated. Scrapers, rotated by driving mechanism 3, function inside 20 the inner tubes 8, 9.

The cooling medium (such as liquefied SO₂) enters the apparatus at 4, whilst the vapours of the cooling medium are drawn off by way of separators 5 through a pipe 6.

In accordance with the invention the inner tubes 8, 9 are fitted, at both ends, into superimposed headers 12 each provided with lower and upper flanges 10, 11. From Fig. 2, it will be evident that the inner tubes 8, 9 extend in fluid-tight manner through tubular branches 13 of the headers, whilst the outer tubes 1 are secured within the inner ends of the branches 13 as by welding. Each header 12 is provided internally with a centrally apertured bottom 14 which curves upwardly round the tubes 8, 9 and merges at about the level of the axes of the tubes into vertical walls 16, thereby affording for the effluent vapour a wide opening 15 surrounded by a well for the cooling medium which well embraces the portions of the tubes 8, 9 that traverse the branches 13. Said walls 16 project above the desired level of the liquid in the pertaining header 12, and preferably extend as far as the upper edge of the flange 11 of the header. In each column of superimposed headers 12, the openings 15 together constitute a continuous shaft which is designated 20 in Fig. 3 and opens at the top into the pertaining separator 5.

Cooling medium enters the well in the topmost 50 header 12 through a bend 17 integral with the inlet 4, and is guided into the wells of the other headers below by means of overflow tubes 18 which project above the bottoms 14 to such extent that the inner tubes 8, 9 are always bathed 55

with cooling medium, right up to the crowns. The overflow tubes 18 in the several headers are offset, in order to prevent the introduced cooling medium from flowing direct into the header next 5 below.

Branches 7 in the base members of the end frames constituted by the superimposed headers 12 serve for the attachment of control, or metering, appliances.

10 As can be clearly seen from the drawing, the headers 12 are superimposed by means of their flanges 10, 11 to form a continuous column devoid of any lateral opening likely to give rise to leakage. In any tier of the tubes, the cooling medium 15 can evaporate uniformly over a large surface. The escaping vapours of the medium can pass, unhindered, from the well spaces 19 into the continuous main shaft 20, from which they are led away, through the separator 5, into the exhaust pipe 6.

15 A particular advantage of the described arrangement is that the cooling surfaces extend as far as the ends of the individual tubes and not, as in the existing types of chiller, merely as far 20 as the bearings.

I claim:

1. A header member, for a chilling apparatus having adjacently disposed tubes for the substance to be treated individually surrounded by 25 tubular cooling jackets except for their end portions, comprising spaced branches adapted to be traversed by said end portions and to interconnect the ends of the cooling jackets in fluid tight relation, and an internal bottom affording a well for cooling medium including said branches, said bottom having an aperture with upstanding walls providing a central vapour escape passage.

2. A header member, for a chilling apparatus 40 having adjacently disposed tubes for the substance to be treated individually surrounded by tubular cooling jackets except for their end portions, comprising spaced branches adapted to be traversed by said end portions and to interconnect the ends of the cooling jackets in fluid 45 tight relation, upper and lower connecting flanges for mounting said header for supporting said condenser or chiller, and an internal bottom affording a well for cooling medium including said branches, said bottom having an aperture with upstanding walls providing a central vapour escape 50 passage.

3. A header member, for a chilling apparatus 55 having adjacently disposed tubes for the substance to be treated individually surrounded by tubular cooling jackets except for their end portions, comprising spaced branches adapted to be traversed by said end portions and to interconnect the ends of the cooling jackets in fluid 60 tight relation, an internal bottom affording a well for cooling medium including said branches, said bottom having an aperture with upstanding walls providing a central vapour escape passage, and an overflow pipe extending through 65 said bottom.

4. A header member, for a chilling apparatus 70 having adjacently disposed tubes for the substance to be treated individually surrounded by tubular cooling jackets except for their end portions, comprising spaced branches adapted to be traversed by said end portions and to interconnect the ends of the cooling jackets in fluid 75 tight relation, upper and lower connecting flanges for mounting said header for supporting said condenser or chiller, an internal bottom

affording a well for cooling medium including said branches, said bottom having an aperture with upstanding walls providing a central vapour escape passage, and an overflow pipe extending through said bottom. 5

5. In a chilling apparatus, particularly for freeing mineral oils from paraffin, having tiers of adjacently disposed tubes, means connecting the ends of the tubes to form a continuous conduit for the substance to be treated, and 10 tubular cooling jackets individually surrounding the tubes except for end portions thereof, end frames of superimposed header members each comprising upper and lower connecting flanges, spaced branches traversed by the end portions of the tubes of one tier and connecting the ends of their tubular cooling jackets, and an internal bottom 15 affording both a well for cooling medium embracing said end portions of the tubes and a central passage for vapours 20 arising from the cooling medium.

6. In a chilling apparatus, particularly for freeing mineral oils from paraffin, having tiers of adjacently disposed tubes, means connecting the ends of the tubes to form a continuous conduit for the substance to be treated, and tubular cooling jackets individually surrounding the tubes except for end portions thereof, end frames of superimposed header members each comprising upper and lower connecting flanges, spaced 25 branches traversed by the end portions of the tubes of one tier and connecting the ends of their tubular cooling jackets, an internal bottom affording both a well for cooling medium embracing said end portions of the tubes and a central passage for vapours 30 arising from the cooling medium, and an overflow pipe extending through said bottom to the well of the next lower header member. 35

7. A chilling apparatus according to claim 6, 40 the inlets and outlets of the overflow pipes in the successive header members being relatively offset.

8. In a chilling apparatus, particularly for freeing mineral oils from paraffin, having tiers of adjacently disposed tubes, means connecting the ends of the tubes to form a continuous conduit for the substance to be treated, and tubular cooling jackets individually surrounding the tubes except for end portions thereof, end frames 45 of superimposed header members each comprising upper and lower connecting flanges, spaced 50 branches traversed by the end portions of the tubes of one tier and connecting the ends of their tubular cooling jackets, an interior apertured 55 bottom, and walls rising from the aperture in said bottom to constitute a peripheral well embracing said end portions of the tubes with a central passage for removal of vapours arising from the cooling medium. 60

9. In a chilling apparatus, particularly for freeing mineral oils from paraffin, having tiers of adjacently disposed tubes, means connecting the ends of the tubes to form a continuous conduit for the substance to be treated, and 65 tubular cooling jackets individually surrounding the tubes except for end portions thereof, end frames of superimposed header members each comprising upper and lower connecting flanges, spaced branches traversed by the end portions 70 of the tubes of one tier and connecting the ends of their tubular cooling jackets, an interior apertured bottom, and walls rising from the aperture in said bottom to constitute a peripheral well embracing said end portions of the tubes 75

with a central passage for removal of vapours arising from the cooling medium, said walls rising to the upper flange of the header member.

10. In a chilling apparatus, particularly for
5 freeing mineral oils from paraffin, having tiers
of adjacently disposed tubes, means connecting
the ends of the tubes to form a continuous con-
duit for the substance to be treated, and tubular
cooling jackets individually surrounding the
10 tubes except for end portions thereof, end frames
of superimposed header members each compris-
ing upper and lower connecting flanges, spaced
branches traversed by the end portions of the

tubes of one tier and connecting the ends of
their tubular cooling jackets, an interior aper-
tured bottom, walls rising from the aperture
in said bottom to constitute a peripheral well
embracing said end portions of the tubes with
a central passage for removal of vapours aris-
ing from the cooling medium, and an overflow
pipe for leading cooling medium from the well
to that of the next lower header member.

11. A chilling apparatus according to claim 10,
10 the inlets and outlets of the successive header
members being relatively offset.

HEINRICH SÜSS.
